Attorney

UNITED STATES PATENT OFFICE

WILL J. ECKER, JR., OF ST. LOUIS, MISSOURI

CARD CASE

Application filed October 31, 1930. Serial No. 492,430.

The object of my invention is to make a card case comprising a folder and a holder. The latter being detachably secured in the former. A further object is to make a holder 5 into which successive sheets of tissue paper may be detachably secured. A further object is to make the holder of such size and conformation as to permit the selective detachable securing of cards to the holder by the use 10 of specially designed sheets of tissue paper.

A further object is to devise a holder to which cards will be detachably secured by means of tissue paper and in which the tissue paper will be slightly larger than the cards 15 and extend over the lateral edges for the purpose of preserving the cards against soiling.

A still further object is to make a holder for securing cards so that a sheet of tissue paper will be positioned between each card 20 and so that each card may be successively removed by removing the sheet of tissue paper immediately above it. Among the further objects of my invention are to devise a card holder, which may be selectively attached in 25 a folder, so that only the cards will be visible and the means of attaching the holder to the folder will not be visible. The holder and folder may be made of few and simple parts that lend themselves readily to multiple production and may be cheaply and easily manufactured, assembled and repaired.

With these and other objects in view my 30 invention has relation to certain novel features of construction and arrangement of parts as will be hereinafter more fully described, pointed out in the claims and illustrated in the drawing in which.

Fig. 1 is an inverted plan view of the card holder showing the means of attaching the sheets of tissue paper, which hold the cards in position.

Fig. 2 is a cross sectional view on line 2-2 of Fig. 1.

Fig. 3 is a plan view of the folder showing the holder attaching means with the cover of the folder shown fragmentally.

Fig. 4 is a transverse sectional elevation of the holder and folder, taken on the line 4-4 of Fig. 3.

Fig. 5 is a plan view of one of the sheets

of tissue paper used in my device, together with one of the cards showing the relative position of the latter and the former when the former is holding the latter in position on the holder.

Fig. 6 is a front elevation of the folder and holder in the assembled position.

Numeral 7 designates the folder and numeral 8 the holder, both generally. The folder 7 is of the book type having the two outside covers 8^a and 9, which are hingedly secured at 10, so that the outside covers 8^a and 9, when the folder is in its closed position, are in sufficient spaced relationship to accommodate the holder 8, together with the cards 60 that may be secured to it. Numeral 11 designates one of the cards that is to be secured detachably in the holder 8. Numeral 12 designates one of the sheets of tissue paper that is used to secure each card to the holder 65 8 and to cover each card. The sheet of tissue 12 is made slightly wider than the card 11, when the card 11 is positioned on the tissue 12, as shown in Fig. 5. In one of the lateral edges of the sheet of tissue 12 are cut the indentations 13. These indentations are used in the manufacture of the sheets of tissue 12 and have no function in use. On one end of the sheet of tissue 12 is formed the rectangular projection 14. On the opposite end of the 70 tissue 12 are formed two rectangular projections 15.

The holder 8 is a rectangular plate made of metal or other suitable material from which are stamped the prongs 16 near one end and 85 the prongs 17 near the other end, as best shown in Fig. 1. Numeral 18 designates two slots, which are stamped in the holder 8, as shown in Fig. 1. The prongs 16 and 17 and the slots 18 all project from the same side of 90 the holder 8. In assembling the cards on the holder the following method is employed:

A card is laid on the holder 8 on the side opposite to the prongs 16 and 17 and the slots 18. The holder 8 is of substantially the same 95 size, but a little larger in width than the card 11. All the cards used are of the same size. All the sheets of tissue paper 12 are of the same size. After the first card has been positioned, as indicated, a sheet of tissue 100

paper 12 is laid over the card. Since the tissue paper is slightly greater in width than the width of the card, if the card is positioned centrally on the holder 8, the edges of the tissue paper will project slightly beyond the edge of the card. The sheet of tissue paper 12 is so positioned that the rectangular projection 14 extends laterally relative the holder 8 on the same side as the prongs 17. The 5 rectangular projection 14 is then folded around the edge and the end of the holder 8 and passed beneath the prongs 17. The projections 15 are likewise folded around the opposite end of the holder 8 and pass under the 10 prongs 16, as shown in Fig. 1. A second card is then laid on the first sheet of tissue paper centrally relative the holder. A second sheet of tissue paper 12 is then positioned over the second card and the projections 14 and 15 15 folded in the prongs 16 and 17 as was the first sheet. The process is thus continued 20 alternating cards and sheets of tissue paper until the desired number of cards has been positioned on the holder. The 25 process is completed by having a sheet of tissue paper cover the uppermost card. It will be seen that as more cards are placed on the holder that in folding over the projections 14 and 15 that they must not only 30 be folded over the edge of the holder, but also over the edges of the preceding cards and sheets of tissue. This in turn means that the part of the projections 14 and 15 that extends under the prongs 16 and 17 will be 35 less for each succeeding sheet of tissue paper. By this means a portion of the end of the projections 14 and 15 of each sheet of tissue paper will be exposed as shown in Fig. 1. The prongs 16 and 17 are then pressed down 40 tightly against the projections 14 and 15 of the sheet of tissue 12, thereby securing the sheet of tissue to the holder and thereby holding the cards to the holder 8, and also in the same relative position in which they were 45 placed when placing them in the holder. This means of holding the sheets of tissue paper may not be, and is often not, sufficient. In order to additionally secure the projections 14 and 15 of the sheets of tissue 12 to the 50 holder 8, the following method is used. Numeral 19 designates a rectangular sheet of leather or imitation leather or other suitable material of the same size as the holder 8. In the sheet 19 are cut holes sufficient to permit 55 the protrusion of the slots 18, when it is placed on the holder 8. The sheet 19 is then glued to both the holder 8 and the protruding projections of each sheet of tissue. That is to say, it is glued to the holder 8 proper and 60 covers the prongs 16 and 17 to which it is glued, and is also in one operation glued to the exposed ends of each sheet of tissue paper. By this means the tissue paper is secured to the rectangular sheet 19 and rectangular sheet 65 19 is secured to the holder.

In order to detachably secure the holder 8 to the folder 7, the following means is devised:

Numeral 20 designates a rectangular plate, made of metal or other suitable material into which are stamped the slots 21. Numeral 22 designates slides in sliding engagement in the slots 21. The ends of the edges of the plate 20 are slightly rounded or bent and the plate 20 is secured to the folder 7 in the position best shown in Fig. 3 by means of stamped projections 23 which pass through the one outside cover of the folder 7 and are bent over at the other end. Owing to the rounded edges of the plate 20, the face of the plate 20 is in spaced relationship with the face of the cover of the holder 8. The distance between the face of the plate 20 and the holder 7 is very slight, for instance one thirty-second of an inch.

Numeral 24 designates rectangular openings in the plate 20 positioned in the line of travel of the slides 22, as best shown in Fig. 3. The rectangular openings 24 are of such size as to permit the insertion therein of the slots 18. In order, therefore, to secure the holder 8 to the folder 7, it is only necessary to position the slots 18 in the rectangular openings 24 and push the slides 22 through the slots 18. In Fig. 3, one of the slides 22 is shown in the locked position and the other is shown in the unlocked position.

Throughout the specification and claims wherever "tissue paper" is employed, applicant wishes it understood that any transparent or translucent material, such as celluloid, cellophane, etc. may be used as an equivalent.

What I claim is:

1. A card holder, prongs formed therein, sheets of tissue paper for securing cards to said holder, projections formed on said sheets of tissue paper, said projections folded around the ends of said holder and secured in said prongs.

2. A card holder, prongs formed therein, sheets of tissue paper for securing cards to said holder, projections formed on said sheets of tissue paper, said projections folded around the ends of said holder and secured in said prongs, a sheet of material secured to said holder and to and over said projections.

3. A card holder, sheets of tissue paper for securing cards to said holder, projections formed on said sheets of tissue paper, means for securing said projections to each other and to said holder.

4. A card holder, cards, sheets of tissue paper, said sheets of tissue paper being of substantially the same size and being folded over the edges of said holder, so that a portion of each succeeding sheet of tissue paper will be exposed, a portion of the sheet of tissue paper in contact with said holder glued to said holder, and a portion of each succeed-

ing sheet glued to the exposed edges of the adjacent sheets.

5. A card folder having slides secured thereto, a card holder having slots secured 5 therein, the slides of said folder being in sliding engagement in the slots of said holder, cards, sheets of tissue paper, said cards being secured to said holder by means of said sheets of tissue paper.

10 In testimony whereof I affix my signature.

WILL J. ECKER, JR.
